INVENTOR,

Joseph U. Meistrell,

BY
James P. Duhamel,
ATTORNEY.

UNITED STATES PATENT OFFICE.

JOSEPH U. MEISTRELL, OF BROOKLYN, NEW YORK.

EJECTOR CONTROL FOR TYPE-BAR MACHINES.

1,382,110.

Specification of Letters Patent. Patented June 21, 1921.

Application filed March 30, 1920. Serial No. 370,025.

To all whom it may concern:

Be it known that I, JOSEPH U. MEISTRELL, a citizen of the United States, and residing at Brooklyn, Kings county, New York State, 5 have invented certain new and useful Improvements in Ejector Controls for Type-Bar Machines, of which the following is a specification.

This invention relates to type-bar machines and more especially to the ejectors and blades for the same and its object is to prevent damage to blades and the machine in case that the mold disk has been set for a bar of certain length and the operator for- 10 gets to set the blades for that length of bar, the device will automatically adjust the blades for a minimum length bar and reduce the range of the ejector blade.

These and other objects of the invention 20 are more fully described in the following specification, set forth in the appended claims and illustrated in the accompanying drawings, wherein:

Figure 1 is a perspective view of the de- 25 vice detached from the type bar machine,

Fig. 2 is a side view of the ejector blade control lever and the latch,

Fig. 3 is a plan view of the latch.

In the drawings, the machine is eliminated 30 and only so many of the ordinary details are shown as may be needed to clearly illustrate and describe the operation of the invention. These few parts are the control lever 5, the ejector blade scale bar 6, the 35 segment 7 and the mold disk pinion 8.

A lever 9, is fulcrumed to the frame of the machine below the vise and the mold disk by means of a clamp 10, and at a point which gives the end 11, a much greater 40 throw than the end 12, the former end being offset at about a right angle. To the end 12, of the lever 9, is secured a rod 13, that connects it with one arm 14, of a bell crank lever which is pivoted by any desired means 45 to the frame of the machine and adjacent the mold disk, and the other end 15 of this lever carries a roller 16, that stands in the path of the pinion 8, as it is shifted outward in setting the mold disk for a new 50 length of bar.

When the pinion 8, is thus shifted outward, it depresses the end 12, of lever 9, and raises the end 11, which carries with it a rod having the reduced portion 18, which 55 forms cam shoulder 19.

The lever 5 carries at its outer end a latch

21, consisting of a sliding plate 22, held on a base plate 23, by the head of a bolt 24, that plays in a slot 25, in the plate 22. The plate 22, is held in its extended position 60 by a spring 26, connected with an arm 27, that causes two slots 28 and 29, one in the plate 22 and the other in plate 23, to offset about half the length of each and through the normally registering parts of these slots 65 extends the reduced part 18, of the rod 17, as shown in Fig. 2.

When the rod 17, is elevated by the move- 70 ment of the pinion 8, and the intermediate parts, the shoulder 19, forces the plate 22 backward. This plate 22, is a pawl which engages the indents in the segment 7, and holds the lever 5, and the scale bar 6, in their proper position, but the above de- 75 scribed action of the pinion 8, thus releases the plate, the latch and the lever and scale, and the parts operated by the former, reduce the blade operation to the minimum and cause the scale to exhibit the ems that are in operation. This is caused by the drop- 80 ping of the rear end of lever 5, with the weight of the parts it carries and the upward movement of the scale bar, when its lowest number is shown.

If it is necessary to disengage the latch at 85 any time, the plate 22, may be retracted by a trigger 30, depending below the plates and operable when the ends of the latch are grasped.

The lever 9, is made in the shape of a yoke 90 to conform with the parts of the machine, but it is obvious that the details of the device may be otherwise arranged or modified without departing from the essential features above described or from the scope of the ap- 95 pended claims.

In case the linotype operator is careless or distracted and sets his mold disk and forgets to shift the control lever for a corresponding 100 ejector blade operation, it is liable to leave a long blade action for a short type bar mold which would seriously damage the blades and liners. The above described mechanism tilts lever 9, the instant the pinion 8, is drawn outward to rotate the disk and this 105 operation withdraws the latch causing the rear end of lever 5, to drop and shift the blades to their minimum number and at the same time the bar 6, is shot upward and the 110 number of ems is exhibited. This will necessitate the proper adjustment of the control lever to correspond with the line mold,

or if this is overlooked, the minimum blade may operate but do no damage.

What I claim as new is:—

1. In an ejector attachment, the combination of a shifting mold disk pinion, an ejector control lever having a latch, and intermediate connecting and operating means between the lever and the mold disk pinion to release the latch when the pinion is shifted.
- 10 2. In an ejector attachment, the combination of a mold disk pinion, an ejector control lever, a latch adapted to hold the lever in a certain position, and a lever operated by the pinion, and connecting means between the lever and the latch to release the latter.
- 15 3. In an ejector attachment, the combination of a mold disk pinion, an ejector control lever, a latch adapted to lock said lever, a toothed segment, a lever operated by the pinion, and a second lever connected with the operated lever and adapted to withdraw the latch from the toothed segment.
- 20 4. In an ejector attachment, the combination of a mold disk pinion, an ejector control lever, a stationary toothed segment, a latch on the lever and adapted to engage the segment, a lever adapted to be actuated when the pinion is shifted, and a rod carried at the outer end of a second lever that is actuated by the latter lever and adapted to shift the latch and release the control lever.
- 25 5. In an ejector attachment, the combination of a mold disk pinion, an ejector control lever having a scale bar, a lever adapted to be operated by the pinion when it is shifted, a sliding latch with a perforation carried by the control lever, a toothed segment adapted to be engaged by the latch, and a bar with a cam shoulder carried at the end of the pinion operated lever and passing through the
- 30
- 35
- 40

perforated latch and adapted to release same by means of the shoulder.

6. In an ejector attachment, the combination of a shifting pinion, a bell crank lever having an arm in the path of the pinion as it shifts, a rod at the other arm of the lever, a lever at the lower end of the rod and pivoted to the frame of a machine, a lever adapted to shift a scale, a sliding plate on the lever and having an opening, a rack segment engaged by the plate to lock the lever, a rod with a cam shoulder carried and actuated by the lever that is pivoted to the frame and adapted to move upward and disengage the latch, and a trigger adapted to operate the latter independently. 45 50 55

7. In an ejector attachment the combination of the ejector control means adapted to be held at a certain position, movable molding means, an intermediate connecting means 60 adapted to effect the release of the ejector control means when the molding means is actuated.

8. In an ejector attachment, the combination of the ejector control means, a pinion 65 adapted to be shifted with its shaft, molding means connected with the pinion, a lever operating the control means and adapted to be locked, and intermediate actuating means operated by the pinion when shifted to unlock the lever. 70

In testimony whereof, I have signed my name to this specification in the presence of two subscribing witnesses, this 13th day of March 1920.

JOSEPH U. MEISTRELL.
